MULTIPLE VALVE CONTROL OUTLET
HYDRANT

George H. Martin, Bogue, Kans.

Application April 28, 1950, Serial No. 158,756

5 Claims. (Cl. 137—110)

1

This invention appertains to novel improvements in water hydrants of the type which are used by fire companies for obtaining a water supply to extinguish fires.

The primary object of the instant invention is to enable one hydrant to be used for supplying water under an increased pressure to a plurality of fire hoses and to permit the successive attachment of fire hoses to the pumper hydrant without interrupting the water supply to the first hose attachment thereto.

Another important object of this invention is to provide a hydrant having a plurality of outlets and to provide control valves for the outlets, two of the valves being mechanically connected together in such a way that when either is open the other is closed.

A further important object of this invention is to provide closure valves for the outlets in a hydrant, the hydrant and the valves being formed in such a manner as to resist freezing, and the valves and outlets being formed to automatically coat with a pump unit, whereby the water pressure may be increased and fire hoses may be successively attached to the hydrant without interrupting the water supply to the initial hose during the early stages of the fire.

These and ancillary objects and structural features of merit are attained by this invention, the preferred embodiment of which is set forth in the following description and illustrated in the accompanying drawings, wherein:

Figure 1 is an elevational view of a fire hydrant, embodying the structural features of this invention, with a portion of the hydrant wall broken away to illustrate the construction and arrangement of the valves;

Figure 2 is a longitudinal vertical sectional view illustrating the mechanically connected valves;

Figure 3 is a transverse sectional view taken on line 3—3 of Figure 1;

Figure 4 is a schematic showing of the conventional lay-out system of fire hoses which are attached to conventional hydrants;

Figure 5 is a schematic showing of the hydrant illustrated in Figure 1 with the inlet valve closed;

Figure 6 is a schematic showing with the inlet valve open and the water supply passing through the hydrant to the first hose attached to the hydrant;

Figure 7 is a schematic showing of the hydrant and pump unit operatively connected thereto; and

Figure 8 is a schematic showing of the lay-out

2

system of fire hoses as taught by this invention.

When using a conventional hydrant, the first fire company arriving on the scene of the fire attaches its hose to the hydrant and, upon opening the inlet valve, the water supply passes through the hydrant and through the hose. When the other fire companies arrive on the scene of the fire, it is necessary to resort to the use of distant hydrants and attach the hoses thereto, or else it is necessary to close the main valve in the hydrant in use so that other hoses can be attached thereto. This results in an interruption of the water supply during the early stages of the fire and at the most crucial time when the water supply is needed. Furthermore, it results in a tie-up of traffic and an increase in the amount of hose used.

Various hydrants have been constructed to avoid these defects and have included valve arrangements whereby successive hoses may be attached to the hydrant in use without interrupting the water supply. However, such constructions, while avoiding the necessity of turning off the water from the hydrant in use, do not permit a multiple number of fire hoses to be attached to a single hydrant. Additionally, the valves in such hydrants are not automatically actuated in response to the water pressure and are not resistant to freezing.

The fire hydrant 10, in its exemplary form, overcomes the latter defects and includes a hollow standard or housing 12, which is formed at its base with a flange 14 secured by bolts 16 to a companion flange 18 on a water main 20.

A partition 22 is transversely mounted in the lower portion of the standard and is centrally formed with an opening 24, the walls of which are beveled to provide a valve seat for a beveled main inlet valve 26. An operating rod 28 is secured at its lower end to the valve and extends axially of the standard, the upper end of the rod being connected to an operating member or hexagon head 30, whereby the rod may be raised and lowered by turning the head 30 to open and close the valve 26.

The standard is provided with a transverse center partition wall 38 forming an upper chamber 32 and a lower chamber 34, the chambers being communicated by means of a port 36 formed in the partition, the port 36 forming a valve seat for a frusto-conical auxiliary inlet valve 40. The valve operating rod 28 extends through the center of the partition 38, the valve seat 36 in the portion being off center, as seen in Figure 2.

An outlet 42 extends laterally from the stand-

ard, adjacent to the base flange 14, and co-axially aligned outlets 44 and 46 are formed at the upper portion of the standard, the ports being in communication with the upper chamber 32. The outlets are provided with closures or caps 48. The outlet 42 is controlled by a beveled valve 50, which is provided with an operating rod 52 extending transversely through the lower chamber 34 and having its opposing end connected to a head 54, whereby the rod may be rotated to move the valve 50 from its seat 56.

The valve 40 is secured to one end of a bell-crank lever 58, which is pivotally secured by a pivot pin 60 to an inwardly and upwardly projecting arm 62. A valve 64 is carried by a link 66 laterally projecting from the upper portion of the crank lever 58 and is adapted to be seated in a valve seat 66, the valve 64 controlling the outlet 44. A spring 68 is secured to an apertured ear 70 projecting inwardly from the standard and has its opposing end bent and attached to an opening 72 in the upper end of the crank lever.

As seen in Figure 4, the conventional lay-out system involves the use of a plurality of hydrants 74 to which the fire hoses 76 are attached. This necessitates the employment of extra long hoses and involves a maximum of labor expenditure with an increase in service time. In using the hydrant 10, the foregoing defects can be avoided, as seen in Figure 8. Thus, with respect to Figures 5 through 8, it is to be noted that the valve 26 will normally be seated in its valve seat and the valve 40 will be open, with the valves 50 and 64 closed. The valve 64 is normally held in a closed position by means of the spring 68, which also retains the valve 40 in an open position.

When the fire company arrives on the scene of the fire, the valve 26 is opened by rotating the valve operating rod 28 by applying a wrench to the head 30. The water supply passes through port 36 and through the outlet port 46, as seen in Figure 6. Of course, a hose is connected to the outlet port 46 by removing the cap 48 prior to opening the inlet valve 26.

Upon the arrival on the scene of other fire companies, the fire hose connected to the outlet 46 is not disconnected, nor is the inlet valve 26 closed. Instead, a pumper 78, which may be driven by the engine of one of the fire apparatuses, is connected to the outlet ports 42 and 44 by means of connecting conduits or branches 80 and 82. The valve 50 is opened by rotating the rod 52 and the water supply is diverted from the port 36 and passes through the port 42 and the connection 82, which is secured to the suction side of the pump. The water supply enters the pumper and passes through the branch 80 into the port 44 to open the valve 64. When the valve 64 is opened by the water pressure, the crank 58 is pivoted about its pivot 60 and the valve 40 is seated in the seat 36. Outlets 84 are provided on the delivery side of the pumper and fire hoses 86, as seen in Figure 8, are connected thereto. Thus the water supply to the initially attached fire hose 88 is not interrupted and the pumper is operatively connected to the hydrant, without disconnecting the fire hose 88. At no time during the attachment of the fire hoses 86 is there an interruption of the water supply to the fire hose 88 and, therefore, a more efficient extinguishing of the fire is obtained, with a reduction in the amount of hose footage needed.

It is to be especially noted that the valves 40

and 64, which control the water supply to the first outlet 46, are mechanically linked or connected together, so that when the valve 40 is opened, when the hose 88 is the only hose attached to the hydrant, the valve 64 is closed. Upon connecting the pumper to the hydrant, as illustrated in Figure 7, the valve 40 is automatically closed due to the opening of the valve 64 under the incoming water pressure. This arrangement of the valves, whereby the valves are automatically operated, prevents the valves from becoming frozen and also eliminates the mechanical actuation of control valves. Also, by locating the shut-off or inlet valve 26 below the ground level, the valve is freeze-proof.

When the pumper is attached to the hydrant, the pressure is increased from the standard city pressure to a high pressure without any interruption in the flow, and when the cap 48 is removed from the outlet 44, no leakage will occur, though the hose connection is already established at outlet 46. In the latter respect, the water pressure will keep valve 64 closed until the pumper is in use, whereupon valve 64 will be opened and valve 40 will close.

Having thus described the invention, what is claimed as new is:

1. A fire hydrant comprising an upright hollow standard having an inlet in the lower portion thereof, a valve controlling said inlet, a rotary stem operatively connected to the valve and extending axially of the standard, a transverse partition in said standard and positioned above the inlet, said partition having an opening formed therein, a control valve for said opening, an outlet projecting from said standard above the partition and means for normally retaining the control valve in an open position, whereby the water supply passes from the inlet through the opening in the partition to the outlet, a second outlet projecting from the standard between the partition and the inlet, a control valve for said outlet, a third outlet projecting from the standard above the partition, a valve for said outlet, connecting means between the valve for the third outlet and the valve for the opening in the partition, whereby when a pumping connection is established between the second and third outlets, the valve for the opening in the partition will be automatically closed, the water supply passing through the second and third outlets through the pumping connection to open the valve for the third outlet and to be discharged through the first outlet.

2. The combination of claim 1, wherein said connecting means includes a bell crank lever vertically pivoted to the standard intermediate of its opposing ends, said valve for the partition opening being carried by the lower end of the lever, a link projecting laterally from the lever and supporting the valve for the third outlet and resilient means connected between the upper end of the lever and the standard.

3. The combination of claim 2, wherein said resilient means is anchored to the standard above the third outlet to urge the upper end of the lever relative to the outlet and thereby hold the valve for said outlet in a closed position.

4. In a hydrant having a valve controlled inlet in its lower end, a transverse partition formed with an opening and positioned above the inlet, a first and second outlet projecting from the hydrant above the partition, a valve for said first outlet, a supporting member vertically pivoted to the hydrant and supporting said valve,

a valve for the opening in the partition carried by the lower end of the supporting member, resilient means connected between the hydrant and the upper end of the supporting member for urging the supporting member relative to the said first outlet whereby the valve for the outlet is normally seated and the valve for the partition is open to permit the water supply to pass through the opening in the partition to the second outlet, a third outlet in said hydrant below the partition, and a control valve operatively associated with said third outlet, said third outlet being connectable exteriorly of the hydrant with the first outlet for establishing, when the control valve for said third outlet is open, a flow from the inlet through the first outlet, the valve for said first outlet being automatically opened and the valve for the opening in the partition being closed.

5. A hydrant comprising an upright hollow standard having an inlet in the lower portion thereof, a first valve controlling said inlet, a stem for said valve extending axially of the standard and disposed through the upper end thereof for manual actuation, a transverse partition in said standard disposed above said inlet and having an opening therein, a second valve for said opening, a first outlet extending from said standard above the partition, resilient means

for normally retaining the second valve in an open position whereby the water supply passes from the inlet through the opening in the partition to the first outlet, a second outlet projecting from the standard below the partition, a third manually operated valve controlling said second outlet, a third outlet extending from the standard above the partition, a fourth valve controlling said third outlet, mechanical means connecting the second and fourth valves so that when one is open the other is closed, whereby when a connection is established exteriorly of the standard between the second outlet and third outlet the second valve is closed upon opening under the water pressure of the fourth valve.
